GOLF PRACTICE VIEWING MIRROR

Jack Pleasants, Somerville, N.J., assignor to Nova Products, Inc., Springfield, N.J., a corporation of New Jersey

Filed Nov. 20, 1964, Ser. No. 82,730

Term of patent 14 years

(Cl. D34—5)

FIG. 1 is a front perspective view of a golf practice viewing mirror showing my new design;

FIG. 2 is a back plan view thereof; and

FIG. 3 is a side view thereof.

I claim:

The ornamental design for a golf practice viewing mirror, substantially as shown.
